ABSTRACT OF THE DISCLOSURE

A die forging machine having one pair of mutually opposed hammers provided with preshaping tools, and another pair of mutually opposed hammers provided with finishing dies. The two pairs of hammers are disposed in a common plane and spaced apart by 90° angles. Compressed gas drives the two pairs of hammers alternately against opposite sides of bar stock introduced between the hammers.

This invention relates to a die forging machine, in which die-carrying hammers blow from opposite sides against the bar stock which is introduced between the dies. A known machine of this type comprises two hammers, which constitute connecting rods driven by eccentrics. Each hammer carries a preforging die and a finishing die one beside the other. A feeding mechanism consisting of a plurality of displaceable grippers, which grip in alternation, is provided for an intermittent feeding of the workpiece. The entire deformation of each workpiece portion is effected by a plurality of hammer blows. As the number of blows per unit of time cannot be indefinitely increased with such eccentric-driven hammers, for design reasons, deforming speeds in excess of 0.3–0.4 meter per second cannot be used. It is impossible or very difficult to forge various workpieces or workpieces of different materials at these relatively low speeds. It is also undesirable to arrange the preforging and finishing dies one beside the other because this gives rise to forging forces which are eccentric with respect to the hammer axis, which coincides with the main axis of the machine. These forces cannot be controlled with economical means at relatively high blowing speeds. Besides, the arrangement of one die beside the other requires larger and heavier hammers.

It is also known to drive hammers by compressed gas and to return the hammer by applying hydraulic pressure from the opposite end, while compressing the gas, so that a mechanical drive for the hammers is eliminated. This results in very high blowing and shaping rates. This hammer drive, however, has not been applied before to the continuous manufacture of die forgings from bar stock but has only been applied to forging processes involving a great deal of manual work on the machine.

It is an object of the invention to eliminate these disadvantages and provide a die forging machine which enables a manufacture of workpieces even from difficultly deformable material in a continuous, highly automatic operation with a long die life and a good shaping to the desired form.

The invention resides essentially in that a pair of hammers provided with finishing dies, and another pair of hammers, which are offset by an angle of 90° from the former and whose axis lies in the same normal plane to the workpiece axis, are provided, said other pair of hammers carrying preshaping dies or preshaping tools, the two pairs of hammers blow in alternation and at least the pair of hammers which carries the finishing dies is adapted to be driven by compressed gas in known manner. The drive by means of compressed gas permits an increase in blowing speed to 15 meters per second and more and

2

ensures that the workpiece is finished by one blow and at high speed and with a short contact time between the tool and the workpiece. This so-called high-energy shaping results in an improved die life and a better filling of the die, and it has been shown that even workpieces which cannot be shaped or can be shaped only with difficulty at lower shaping speeds can now be manufactured with good or very good success. Materials which cannot be forged at normal blowing speeds exhibit different properties at higher forging speeds. To ensure a favorable distribution of material in the finishing die, almost any workpiece must be preshaped. In many cases, this preshaping may reside only in bending or stretching. The additional pair of hammers is provided for preshaping. Due to the provision of a separate pair of hammers, the previously occurring, eccentric stresses on the hammers, the hammer guides and the machine frame are avoided. Such stresses would be intolerable during shaping operations at high speed. Besides, each hammer can be designed with small dimensions and with a light weight as it must carry only one die or tool so that it can be accelerated to a very high velocity by a desired, predetermined blowing energy. The preshaping may be effected in a plurality of blows. During the preshaping, the workpiece may be rotated and may also be displaced in its longitudinal direction. In many cases it will be necessary to rotate the workpiece through 90° when it has been preshaped so that the workpiece is in its correct position relative to the finishing dies. The arrangement according to the invention is particularly desirable for forging cranked portions because in this case the finishing dies can be applied immediately after the workpiece has been prebent or offset by the preshaping tools without need for rotating the workpiece.

An embodiment of the invention is shown by way of example on the accompanying drawings, in which

FIGS. 1 and 2 show a die forging machine in a sectional view taken transversely to the workpiece axis and in a sectional view taken along this axis. For the sake of clearness, the feeding mechanism and other details are not shown.

45 A forging box 1 forms guides 2 for four hammers 3, 4, which are angularly spaced 90° apart and whose axes lie in the same vertical plane. The hammers 3, 4 are connected by rods 5 to pistons 6, which are slidable in cylinders 7. The blowing movements of the hammers 3 and 4 are directed toward each other and effected by compressed gas, which does not act directly on the pistons 6, but operates an auxiliary piston, not shown, from which the movement is hydraulically transmitted by the supply conduits 8 to the pistons 6. The return of the pistons 6 to their initial position and of the hammers 3, 4 to their position of rest is effected by the application of pressure liquid to the rod ends of the pistons 6 through the conduits 9. During the blowing movement, the pressure fluid is displaced from this end of the piston into a pressure accumulator 10 associated with each piston.

60 The two hammers 3 carry pre-shaping dies 11 and the hammers 4 are provided with the finishing dies 12. When the bar stock has been heated, it is moved between the pairs of hammers 3, 4 by a feeding mechanism, which is not shown. While the hammers 4 are retracted, the bar end is then preforged by means of the hammers 3 and the preshaping tools 11. The workpiece may then be rotated through 90° and is subsequently finished by a single blow of the hammers 4 and the finishing dies 12. A temperature measuring instrument (not shown) checks each workpiece for the correct forging temperature and by means of an electric control circuit initiates the automatic forging cycle only when the forging temperatures are within the desired, adjustable range. When the first workpiece has been finished, the bar is advanced to a suitable extent and the entire cycle is repeated.

What I claim is:

1. A die forging machine, which comprises a first pair of mutually opposite hammers, each of which carries a pre-shaping tool, a second pair of mutually opposite hammers, each of which carries a finishing die, said pairs of hammers being disposed in a common plane and spaced from each other by an angle of 90°, and hammer drive means for driving said pairs of hammers in alternation to perform blows against opposite sides of bar stock introduced between said hammers in a longitudinal direction which is normal to said plane, said hammer drive means comprising a compressed gas source for driving said second pair of hammers.

2. A die forging machine, which comprises a first pair of mutually opposite hammers, each of which carries a pre-shaping tool, a second pair of mutually opposite hammers, each of which carries a finishing die, said pairs of hammers being disposed in a common plane and spaced

from each other by an angle of 90°, and hammer drive means for driving said pairs of hammers in alternation to perform blows against opposite sides of bar stock introduced between said hammers in a longitudinal direction which is normal to said plane, said hammer drive means comprising a compressed gas source for driving said first and second pairs of hammers.
